ELECTRIC RANGE

Robert John, New York, N. Y.

Application June 27, 1932, Serial No. 619,570

9 Claims. (Cl. 219—37)

This invention relates to electric cooking ranges of the type comprising one or more heating elements capable of providing heat by passing an electric current through electrically resistant material; it has as its principal object, the provision of means for automatically removing or neutralizing odors formed in the process of cooking, to the end that such odors may be prevented from pervading the kitchen and other parts of the house or apartment.

As is well known, such odors may be prevented from spreading by the conventional practice of providing a hood over the cook stove and an exhaust fan whereby the air in the vicinity of the stove is constantly being removed; or by the production of ozone in the kitchen, which acts as a deodorant by giving up one atom of oxygen to combine with the unsaturated compounds of which smells are constituted, whereupon the ozone residue consists merely of normal atmospheric oxygen. The present invention may be used to employ either of the foregoing deodorizing agencies, or a combination of both of them, and provides a means for such employment whereby either or both of these agencies are placed in effect by the act of closing the manual switch controlling the flow of current to one or more of the heating elements; and such effect is automatically continued subsequent to the opening of the manual switch, such continuance being capable of regulation to cover the period during which hot foods, while no longer cooking, are still exposed in containers in the kitchen and are still capable of giving off odors.

My invention comprises an electrically operated ozonizer or an electrically operated exhaust fan, or both in combination, either or both of which are wired in parallel with each separately controlled electrical heating element of the range, whereby the closure of one or more of the manual switches governing said heating elements supplies electro-motive force to said ozonizer or said blower or to both of them, as the case may be; and a thermostatic switch which, when closed by the heat generated by said electrically heated elements, is capable of continuing the flow of electro-motive force to said ozonizer or said fan or both of them after the manual switch above referred to is opened for such period as may be desired.

Other objects and advantages of the invention will appear in the following description of the preferred embodiment of the invention shown in the attached drawing of which:

Figure 1 is a perspective view of an electric range embodying my invention; and

Figure 2 is a schematic diagram of the electrical connections.

Referring more particularly to the drawing, 10 indicates in general the electric range, 11 indi-

cates in general the ozonizing unit and 12 indicates the exhaust fan. As shown in Figure 1, the ozonizing unit 11 is preferably positioned upon the range 10, while the exhaust fan may be positioned as shown in the wall to the rear of the range or it may be positioned in a hood placed above the range.

In Figure 2 the heater elements, of which for convenience only three are shown, are indicated at 13. The heater elements 13 are energized through the electric circuits 14 from supply line 15. Switches 16 are provided in each of the circuits 14 for connecting the elements 13 to the line 15. The ozonizer unit 11 comprises an ozonizing element 17 which may be the same as that shown in my copending application, Serial No. 585,101, filed January 6, 1932.

As described in that application, the ozonizing element comprises a dielectric plate having electrodes secured to the opposite side thereof, one of which is exposed to the atmosphere. The ozonizing element is connected to the high voltage winding 18 of a transformer 19. One terminal of the low voltage winding 20 of the transformer 19 is connected to one wire 21 of the supply line 15 through the conductors 22 and 23. The other terminal of the low voltage winding 20 is connected to one terminal of each of the heating units 13 through the conductors 24 and 25. It will be noted that, whenever any of the switches 16 are closed, the low voltage winding 20 is energized from supply line 21 through conductors 23, 22, 24 and 25 back to supply line 26 through the switch 16 and one side of the heater circuit 14.

The conductor 25 is also connected to one terminal of thermostatic switches 27 which are positioned adjacent the heating units 13. The thermostatic switches 27 may be of conventional design and if an exhaust fan 12 is included in the circuit with them, they should preferably be of the snap disc or element type so as to be able to break the relatively heavy current taken by such fan. The thermostatic switches are normally open and are adapted to close when the temperature of the heater elements is above a predetermined point, and are adapted to remain in a closed position until the temperature of the heater elements falls below a predetermined point. The other terminals of the thermostatic switches 27 are connected to the supply line 28 by conductor 29. It is to be noted that the closure of any one of the switches 16 or the thermostatic switches 27 will complete the circuit to the low voltage winding 20 of the transformer 19. Also the winding 20 will be maintained in circuit until all of the thermostatic switches 27 return to an open position.

It is also contemplated in this invention to connect a motor 29 of the exhaust fan 12 in parallel with the low voltage 20 of the transformer 60

19. Such a connection is shown in Figure 2 wherein conductors 30 and 31 are connected to conductors 22 and 24 respectively and are connected to the motor 29.

5 It will thus be seen that both fan 12 and ozonizer 11 are placed in operation whenever any switch 16 is closed. As soon as any one of the heating elements reaches a temperature above a predetermined point, its corresponding thermo-
10 static switch 27 will be closed to maintain the fan and ozonizer in operation. The electric range is intended to be used for cooking ordinary foods or comestibles, and it is well known that certain foods emit a disagreeable and penetrating odor
15 upon being heated. An exhaust fan 12 is effective to eliminate such odors to a certain extent and an ozonizer such as described in my copending application above described is also effective to eliminate such odors. It is therefore contemplated
20 that either the fan 12 or the ozonizer 11 may be used singly or that they may both be used in combination. As is also well-known, heated foods emit odors after the supply of electrical energy to the heating units has been interrupted.
25 The thermostatic elements 27 are so placed as to be heated by the heat retained by the heating elements 13 and by the heated food placed thereon. Since the thermostatic elements maintain the fan 12 and ozonizer 11 in operation until the
30 temperature of the heating units and food thereon drops below the temperature at which odors are emitted, the present invention is effective to eliminate all cooking odors.

If desired, individual switches 32 and 33 may be placed in the circuits of the low voltage transformer winding 20 and the fan 12 respectively, such that either or both of these devices may be maintained out of operation at the option of the operator.

40 While I have described the preferred embodiment of my invention in connection with an electric range, it is understood that the invention is applicable to devices in which heat is produced by other means than electric power, and that
45 the structure and arrangement of parts may be varied within the scope of the invention and of the following claims.

What I claim is:

1. In a device for heating comestibles, a heater
50 for said comestibles, means for initiating operation of said heater, a device for eliminating odors produced by said heated comestibles, said means also being effective to initiate operation of said odor eliminating device and means responsive to the temperature of said heater and comestibles to continue the operation of said odor eliminating device after said heater has been rendered inoperative and to discontinue the operation of said odor eliminating device when the temperature of said heater and comestibles drops to a predetermined point.

2. In a device for heating comestibles, a plurality of heaters, a device for each of heaters for initiating operation thereof, means for eliminating the odors produced by said heated comestibles, each of said devices being effective to initiate operation of said odor eliminating device and means adjacent each of said heaters, responsive to the temperature of said heater and comestibles for maintaining said odor eliminating device in operation until the temperature of said heater and comestibles drops to a predetermined point.

3. In an electric range, a heater unit, a switch for connecting said heater unit to a source of electric power, an ozonizer, said switch also being effective to connect said ozonizer to a source of power, and temperature responsive means for maintaining said ozonizer in connection with its source of power when the temperature of said unit is above a predetermined point. 5

4. In an electric range, a plurality of heater units, a switch for each of said heater units for connecting said units to a source of electric power, an ozonizer, each of said switches also being effective to connect said ozonizer to a source of power, and a temperature responsive means for maintaining said ozonizer connected to its source 15 of power when the temperature of any of said heater units is above a predetermined point.

5. In an electric range, a plurality of heater units, a switch for each of said heater units for connecting said units to a source of electric 20 power, an ozonizer, each of said switches also being effective to connect said ozonizer to a source of power, and a temperature responsive means adjacent each of said heater units for maintaining said ozonizer connected to its source of power 25 when the temperature of any of said heater units is above a predetermined point.

6. In an electric range, a heater unit, a switch for connecting said heater unit to a source of electric power, an exhaust fan, said switch also 30 being effective to connect said exhaust fan to a source of power, and temperature responsive means for maintaining said exhaust fan in connection with its source of power when the temperature of said unit is above a predetermined point. 35

7. In an electric range, a plurality of heater units, a switch for each of said heater units for connecting said units to a source of electric power, an exhaust fan, each of said switches also 40 being effective to connect said exhaust fan to a source of power, and a temperature responsive means for maintaining said exhaust fan connected to its source of power when the temperature of any of said heater units is above a pre- 45 determined point.

8. In an electric range, a plurality of heater units, a switch for each of said heater units for connecting said units to a source of electric power on an exhaust fan, each of said switches 50 also being effective to connect said exhaust fan to a source of power, and a temperature responsive means adjacent each of said heater units for maintaining said exhaust fan connected to its source of power when the temperature of any 55 of said heater units is above a predetermined point.

9. In combination with an electric range, a heating element, a switch for connecting said element to a source of power, an ozonizer, an ex- 60 haust fan, said switch also being effective to connect said ozonizer and said fan to a source of electric power, temperature responsive means for maintaining said fan and said ozonizer connected to their sources of electric power when the tem- 65 perature of said heater is above a predetermined point and to disconnect said fan and ozonizer from their source of power when the temperature of said heater unit falls below a predetermined point.

ROBERT JOHN.
